ATTORNEY

UNITED STATES PATENT OFFICE

ARTHUR EDWARD WILLIAM JAMES, OF WORCESTER, ENGLAND, ASSIGNOR TO
HEENAN & FROUDE LIMITED, OF WORCESTER, ENGLAND

REFUSE DESTRUCTOR

Application filed November 19, 1928, Serial No. 320,438, and in Great Britain June 25, 1928.

This invention relates to improvements in the furnaces of refuse destructors of the type in which the grate of the furnace is formed to slide horizontally or in an inclined direction to remove the clinker therefrom, the clinker falling on to a table, platform or the like arranged below the grate.

According to the invention a moving shelf, table or platform is arranged below and attached to the moving grate, or is caused by other suitable means to move with it or independently of it on to which the clinker falls when the grate is withdrawn and from thence to an undergrate or bench when the grate is returned to its working position, the clinker remaining on the undergrate or bench until it is removed therefrom manually or by mechanical or other means so that its heat may be utilized for igniting the fresh charge of refuse and preheating the air for combustion.

The invention will be described with reference to the accompanying drawings:—

Fig. 1. Vertical section through the furnace showing the grate in the normal working position.

Fig. 2. Vertical section through the furnace showing the grate partly removed from the furnace and the clinker therefrom being discharged on to the moving shelf or table.

The sliding grate A forming the grate proper of the furnace is mounted in the furnace so that it can be withdrawn therefrom, the grate being moved by an hydraulic ram B as shown in the drawings or it may be moved manually, by mechanical means or in any other suitable and convenient manner. A fixed horizontal or slightly inclined or other suitable form of dead plate C is arranged at the side of the furnace opposite to that through which the grate A slides out of the furnace to make a joint with the grate when the latter is in its normal working position and a vertical or steeply inclined or other suitable form of plate D is arranged at the side of the furnace through which the grate slides out of the furnace to make a joint with the grate when the latter is in its normal working position and to ensure that the clinker is scraped off the grate A when the latter is moved away from the furnace.

A shelf or table E is arranged below the sliding grate A, the inner end of the grate A being connected by the bars *a* to one end of the shelf or table E or is caused by other suitable means to move with it so that as the grate A is moved out of the furnace the shelf or table is pulled in under the furnace to receive the clinker as it is scraped off the grate by the vertical or steeply inclined or other form of back plate D.

The shelf or table E slides over an undergrate or bench F on to which the clinker is deposited by the sliding shelf or table E when the grate proper is returned to its normal working position and the shelf or table E moves from under the furnace. A depending plate G or other device affixed to the wall of the furnace may be employed to scrape the clinker off the shelf or table E.

The front end *e* of the shelf or table E is preferably formed to act as a pusher so that on the next movement of the grate proper to discharge the clinker, the drawing in of the shelf or table will push the previously deposited clinker off the undergrate or bench F into a chute H or any suitable receptacle by which it may be removed from the furnace.

This arrangement of sliding shelf or table and undergrate or bench allows the clinker discharged from the grate to lie under the latter for any desired length of time so that its heat may be utilized for igniting the fresh charge of refuse and to preheat the air for combustion.

What I claim is my invention and desire to protect by Letters Patent is:—

1. In a refuse destructor furnace of the type referred to the combination with a sliding grate and ram for operating the grate, of stationary means for removing the clinker from the grate when this latter is withdrawn from the furnace, a moving shelf on to which the clinker falls arranged below and rigidly connected to the grate, stationary means for removing the clinker from the shelf when this latter is removed from the furnace, an undergrate arranged below the shelf on to which the clinker falls from the shelf and from which it is removed by the shelf on the

succeeding passage of this latter into the furnace and a hopper to receive the clinker from the under grate.

2. In a refuse destructor furnace of the type referred to the combination with a sliding grate and ram for operating the grate, of a stationary vertical plate for removing the clinker from the grate when this latter is withdrawn from the furnace, a moving shelf on to which the clinker falls arranged below and rigidly connected to the grate, a stationary vertical plate for removing the clinker from the shelf when this latter is removed from the furnace, an under grate arranged below the shelf on to which the clinker falls from the shelf and from which it is removed by the shelf on the succeeding passage of this latter into the furnace and a hopper to receive the clinker from the undergrate.

20 In testimony whereof I have hereunto set my hand this 7 day of Nov. 1928.

ARTHUR EDWARD WILLIAM JAMES.
